US00D519637S

(12) **United States Design Patent** (10) Patent No.: **US D519,637 S**
(45) Date of Patent: **** Apr. 25, 2006**

(54) **SUPPORT BRACE**

(75) Inventors: **William E. Nordt**, Charles City, VA (US); **Ian D. Kovacevich**, Charlotte, NC (US); **Kevin J. Dahlquist**, Charlotte, NC (US); **Tom J. Philpott**, Charlotte, NC (US)

(73) Assignee: **Nordt Development Co., Inc.**, Charles, VA (US)

(**) Term: **14 Years**

(21) Appl. No.: **29/209,971**

(22) Filed: **Jul. 22, 2004**

(51) LOC (8) Cl. **24-04**

(52) U.S. Cl. **D24/190**

(58) Field of Classification Search **D24/190; 602/1, 5, 20, 21, 23, 26, 60-64; 128/DIG. 20**
See application file for complete search history.

(57) **CLAIM**

The ornamental design for a support brace, as shown.

DESCRIPTION

FIG. 1 represents a first perspective view of the front of support brace of the present invention;

FIG. 2 represents a front elevational view of the support brace of the present invention;

FIG. 3 represents a top plan view of the support brace of the present invention; and,

FIG. 4 represents a side elevational view of the support brace of the present invention.
